[57] CLAIM

The ornamental design for a arrow fletching protective cover, as shown and described.

DESCRIPTION

FIG. 1 is a front elevational view of the arrow fletching protective cover of the present invention;

FIG. 2 is a rear elevational view of the arrow fletching protective cover of FIG. 1;

FIG. 3 is a left side elevational view of the arrow fletching protective cover of FIG. 1;

FIG. 4 is a right side elevational view of the arrow fletching protective cover of FIG. 1;

FIG. 5 is a top plan view of the arrow fletching protective cover of FIG. 1;

FIG. 6 is a bottom plan view of the arrow fletching protective cover of FIG. 1; and,

FIG. 7 is a top, front, right side perspective view in a open position of the arrow fletching protective cover of FIG. 1. The broken line showing in FIG. 7 is for illustrative purposes only and forms no part of the claimed invention.
